[57] **CLAIM**

The ornamental design for a shoe sole, as shown and described.

DESCRIPTION

FIG. 1 is a bottom plan view of a shoe sole showing my new design;

FIG. 2 is a left side elevational view thereof;

FIG. 3 is a right side elevational view thereof;

FIG. 4 is a front elevational view thereof; and,

FIG. 5 is a rear elevational view thereof.

The broken line showing of a shoe upper in the figures is environmental only and forms no part of the claimed design.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 352,386

DATED : November 15, 1994

INVENTOR(S): Ricardo Vestuti

It is certified that error appears in the above-identified patent and that said Letters Patent is hereby corrected as shown below.

On the title page, item [19]: Delete "Vestuti et al." and insert--Vestuti--

In item[75], After "Inventors:" delete the following name from the list of inventors:

Christian Tresser, both.

Signed and Sealed this

Fourteenth Day of February, 1995

Attest:

BRUCE LEHMAN

Attesting Officer

Commissioner of Patents and Trademarks
